Application December 26, 1940, Serial No. 371,816

15 Claims. (Cl. 22—3)

The following description relates to an invention in a machine for automatically casting and finishing stereotype plates. More specifically it provides for performing the successive operations of casting the plate in the mold, removing it from the mold and matrix, and finishing the plate by successively shaving the excess metal from the inner concave surface, trimming off the riser or tail of the casting and disposing of the same and ultimately delivering the finished plate in cooled condition. While each of the above operations has previously been done mechanically, the arrangement of such machines for successive cyclical operation and powered from a common motor is a distinct advance over prior practice.

One of the objects of my invention is to provide improved casting means by which the parts of the mold are held in locked position during the casting operation following which the back of the mold is separated from the cast plate and the latter is then placed upon a gravity runway in such manner that it is stripped from the core and caused to travel by gravity into position to be finished.

A further object of the invention is to provide timed mechanism which will receive the freshly cast plate and position it in the finishing arch, effect the shaving and trimming operations in timed sequence and dispose of the tail separately from the finished plate.

Among the objects of my invention is to provide for successively stopping the plate in the several stations in which operations are performed and to follow each of those operations with automatic release of the plate for further travel.

One of the objects of my invention is to render automatic and mechanical, the movement of the plate from the time it is cast to the moment of delivery and to carry out the several steps of the operation without the necessity of attention by the operator.

Incidental to the carrying out of this invention, I have provided means consisting of the controlling mechanism by which the several operations are carried out in timed sequence.

An additional object of this invention has been to provide a common source of motive power by which each of the several devices are caused to function in the desired manner and in the appropriate sequence.

As exemplifying the preferred means for carrying out the purposes of the invention above set out and such other purposes as may appear, I

have shown in the accompanying drawings one embodiment of the invention. In these drawings

Fig. 1 is a side elevation of the first part of the machine showing the means for casting the stereotype plate, stripping it from the matrix and then from the core;

Fig. 2 is a side elevation of the subsequent part of the machine where the plate is delivered by gravity, shaved, the tail trimmed off and delivered separately from the plate and the latter then cooled and released;

Fig. 3 is a top plan view of the first mentioned part of the machine;

Fig. 4 is a top plan view of the second mentioned part of the machine;

Fig. 5 is a side elevation partly in section of the first part of the machine positioned while delivering the plate from the core to the gravity runway;

Fig. 6 is a plan view of the casting box and core;

Fig. 7 is a vertical longitudinal section of the shaving, trimming and tail delivery means;

Fig. 8 is an end elevation of the line 8—8 of Fig. 7 showing the tripping mechanism for the tail delivery;

Fig. 9 is a vertical section along the longitudinal axis of the machine showing the trimming mechanism with its associated stop means and

Fig. 10 is a vertical elevation on the line 10—10 of Fig. 2 showing the power gearing in greater detail.

Broadly speaking, the invention comprises the correlated arrangement and operation of pouring or casting the plate, its delivery to a gravity runway with successive stops for finishing and cooling, and with means between the last two stations for diverting and delivering separately the surplus tail of the cast plate. The main frame

11 of the machine is provided on each side with a ribbed track 12 generally horizontal and running inward from the front end of the machine. This provides a track for the parts of the casting box 13. The latter comprises a mold 14 in

which the appropriate matrix or flong is carried. Each side of the mold 14 carries a bracket 15 having a horizontally extending arm 16. On each bracket 15 there is journaled a wheel 17. This wheel has a V-shaped periphery fitting the ribbed track 12 upon which it rolls. The forward end of the arm 16 carries an adjustable eccentric stud

18. This stud forms a bearing for the roller 19. The latter is guided between the opposing tracks 20, 21 on the inner side wall of the main frame 11. The upper portion of the bracket 15 has a

downwardly extending track 22 for co-operation with a core locking mechanism.

Outwardly on each side of the casting box 13 and the main frame 11, there is a side shield 23 shown in Fig. 1. This side shield has a stud 24 which forms a pivot for a bell crank lever 25. This lever at one end has a roller 26 which is carried in the track 22. The opposite end of the lever 25 is made in the form of a hook 27 which co-operates with a part of the core to lock the latter in casting position. The side shield 23 has an inwardly extending track 28 controlling the travel of the wheel 17 on the track 12.

The core 29 is mounted upon a bracket 30. On each side of the core is a pin 31 which is received in the locking hook 27 in the assembling movement of the casting box.

The core has a backwardly directed extension 32 which forms a stop for the tilting movement of the core.

The core itself is supported on a pair of rollers 33, one on each side and traveling on the ribbed track 12.

In the casting position, the lower end of core 29 rests upon a spring-seated support 34 which has a lower stop ring 35. This support swings on stud 36 located on bracket 37 which in turn rests upon a cross beam 38 of the main frame. The exact height desired for the support 34 is obtained by the adjusting screw 39. The spring 40 serves to cushion the support in its downward movement.

The power for operating this casting box is derived from motor 41. The motor shaft carries a pinion 42 which drives a ring gear 43. This gear is on a shaft 44. The shaft 44 has a worm 45 in mesh with a gear 46. This gear is on the end of shaft 47. As shown in Fig. 10 this shaft also has a worm 48. The worm 48 delivers power to gear 49, the shaft 50 of which has a beveled gear 51. A similar beveled gear 52 drives its shaft 53 and applies power to the rotary cam 54.

A rock shaft 55 journaled in the frame (Fig. 3) has a crank 56 at one end. This crank travels in the cam track in the cam 54, thus causing the shaft 55 to oscillate. A rock arm 57 fixed on shaft 55 terminates in a gear sector 58. A shaft 59 also journaled in the opposite sides of the main frame 11 carries a gear 60. This gear 60 meshes with the gear 58 on the rock arm 57. In this way shaft 59 is given a limited rotation in one or the other direction by the rocking gear 58.

At opposite ends of the shaft 59 cranks 61, 61 are provided. Links 62 connect these cranks 61, 61 with pivots 63 on opposite sides of the casting box 13.

It will be evident that as the cam 54 rocks shaft 55 the latter by means of its gear 58 will throw the cranks 61, 61 back and forth thus reciprocating the casting box 13 on the tracks 12, 12. This movement retracts the casting box and serves to separate the cast plate from the matrix as soon as the core has been unlocked.

The movement of the core 29 with the cast plate P is first to the left of Fig. 5 and then in a tilting direction bringing the core beyond the horizontal position with the plate stripped from it and resting upon the rollers 79 of the inclined runway (Fig. 5). To effect this movement shaft 59 is also provided with a Geneva motion 64 comprising a locking disk 65, lever 66 and pin 67. This device will of course oscillate when the shaft 59 is rotated by the gear 60. A stub shaft 68 extends inwardly from one side wall of frame

11 slightly below the shaft 59. This stub shaft has fixed upon it a Geneva wheel which fits the locking disk 65 and receives pin 67. Motion given to rock shaft 68 by the Geneva wheel 69 is imparted to rock arm 70. This in turn is connected by link 71 to a rock arm 72. Rock arm 72 is fixed on rock shaft 73. A long arm 74 is also fixed to rock shaft 73 and is connected at its opposite end by means of link 75 to the upper portion of the core 29.

The lower end of the bracket 30 which forms the back of the core, has pivoted thereto a pair of struts 76, 76. The opposite ends of the struts are journaled on stud 77 extending inwardly from the sides of the frame 11. A stop 78 is provided on the nearer side of the frame 11 to engage the extension 32 on the core 29 and thus limit its movement.

In the operation of the mechanism above described the core will move from the vertical position as shown in Fig. 1 to the inclined position shown in Fig. 5. During this retracting and tilting movement the cast plate P will strike the roller 79 of the inclined runway before the extension 32 strikes the stop 78. As a consequence the plate P will be stripped from the core and will slide down the runway by gravity.

The features of construction of the casting box 13 including mold 14 and core 29 are similar to those described in prior Patents 1,009,272 and 1,433,555 to which reference is made for further details.

Provision is made for automatic pouring of the stereotype metal to the casting box at the initial stage of the cycle. This mechanism includes a tank 80 in which the molten metal remains until lifted through the lift pump 81. The plunger rod 82 of the pump is operated by means of a rock shaft 83 supported on a bracket 84. One arm 85 of the rock shaft 83 has an adjusting means 86 by which the throw of the pump plunger 82 may be varied.

A rod 87 connects the adjusted arm 85 with one end of a bell crank 88. This bell crank is pivoted on a bracket 89 mounted in turn upon the outside of the frame 11. The second end of the bell crank 88 carries a roller 90 which travels within the groove of the rotary cam 91. The cam 91 is mounted upon the shaft 53 outside of the cam 54.

The relation of the cam 91 to the cam 54 is such that the charge of molten metal is lifted by the pump plunger 82 and driven through the pipe 92 for delivery to the casting box while the latter is in locked position as shown in Fig. 1.

The retraction of the mold 14, and the tilting of the core 29 and cast plate P into the position shown in Fig. 5 follows as soon as the cast plate P has solidified. When the plate P rolls beyond the core 29, the latter is returned to the casting position shown in Fig. 1, and immediately receives another charge of molten metal. In this way, since the plate is cast as soon as the parts of the casting box 13 are locked, sufficient time will elapse for solidification before the casting box is unlocked and the core 29 and plate P delivered to the runway.

As the plate rolls down the runway it passes over the shield 93 and into the shaving arch 94. It is there brought to a stationary position by means of a stop 95 engaging a tongue on the plate P (Fig. 7).

Simultaneously with the stopping of the plate, it is lifted by a section 96 of the runway so that the plate fits against the shaving arch 94 as

shown in Fig. 9 and thus in position for the finishing operations of shaving the concave interior and of trimming the tail T.

It is desired to reciprocate the stop plate 95 periodically so that the plates are successively arrested and after the tails have been trimmed off and removed, the plates may again be free to gravitate into the cooling section. The means for reciprocating this stop 95 is associated with the plate shaving mechanism. The worm 48 (Fig. 10) rotates a gear 97 (Fig. 7) and this is keyed to a rotary sleeve 98 suitably journaled at 99, 99 in the frame. The sleeve carries the customary shaving blade or knife 100 and in spaced relation thereto is a mounting 101 for the rotary saw 102.

The lower end of the sleeve has a rotary cam 103 with a cutaway portion 104.

The lower portion of the stop plate 95 carries a roller 105 opposite the cam 103. A compression spring 106 holds the stop plate 95 in elevated position with the roller 105 against the cam 103. Thus the stop 95 is held down in inoperative position until such time as the roller 105 is lifted into the cutaway portion 104. At this moment the stop plate 95 arrests the plate P and allows it to be lifted against the shaving arch and to be operated upon the shaving knife 100 and the rotary saw 102. Before the saw has completed its travel against the plate, the stop will have been retracted by the larger diameter of the cam 103 and the tail T of the plate will then be free to continue down the runway.

The sleeve 98 is hollow for the greater portion of its length as shown in Fig. 7. The shaft 107 is journaled axially of the sleeve and at its upper end has a keyed gear 108. This gear is in contact with the gear wheel 43 (Fig. 10) and thus receives relatively rapid rotation.

The lower end of the shaft 107 carries the gear 109. An idle gear 110 on shaft 111 transmits power from gear 109 to pinion 112 in the mounting 101. Pinion 112 is on a shaft 113 and this latter at its outer end carries the rotary saw 102.

At its lower end beyond the bearing 99, sleeve 98 has a gear 114 and this in turn meshes with gear 115 on shaft 116 in the bearing 99. Shaft 116 is extended to carry a rotary cam 117.

A short section 118 of the runway is pivoted to the frame at 119 (Fig. 8). Part of this section carries a transverse bar 120 and an elevated roller 121. This roller rests upon cam 117. In this way the section 118 of the runway is dropped around the pivot 119 in the manner indicated in Figs. 7 and 8 to permit the tail T of the casting to go down the chute 122. This excess material may then be remelted for subsequent use.

As soon as the tail T has been disposed of, the cam 117 restores the section 118 to its normal position and provides for transferring the plate P in trimmed and shaved condition to the cooling stand 123.

A stop 124 is provided across the lower end of the cooling stand. The stop is connected by a link 125 to a lever 126. This lever is pivoted on a portion of the frame as shown in Fig. 2 and normally rests against the cam 127 (Figs. 2, 7 and 9). It will be evident that a single rotation of the cam shaft 116 will release a cooled plate and divert a tail section, thus providing for the cooling stand 123 to receive for cooling the last plate just finished.

The interval of operations of the several co-operating features of the invention have been separately described and explained above. The

advantage of this machine is that it receives power from the common motor 41 and by means of appropriate gearing carries out the several functions in the desired order. Thus as soon as

5 the cam 54 has locked the casting box, a charge of molten metal is automatically delivered to the casting box. The cast stereotype plate remains in the mold until solidified when the casting box is mechanically broken open by the retraction of the mold 14 and the tilting of the core over upon the runway.

10 The core is lowered to a point below that at which the plate rests upon the runway thus causing the separation of the plate from the core. 15 The plate travels by the force of gravity alone into the shaving arch where it is then stopped, lifted into position against the arch and finished first by shaving and subsequently by trimming.

20 On mechanical release from the shaving arch at the conclusion of these operations the plate travels by gravity to the cooling stand.

Prior to delivery of the plate to the cooling stand, the severed tail will have been diverted to 25 its delivery chute and a cooled plate removed from the cooling stand to make room for the one being delivered.

The operation of these several devices in timed sequence provides for rapid, efficient and economical operation of casting stereotype plates. 30 The conjoint use of the devices above described permits variation in arrangements, proportions and details within the scope of my invention as defined in the following claims.

35 What I claim is:

1. In a stereotype plate making machine, an inclined runway having an upper receiving end, a lower delivery end and an intermediate portion, a two-part casting mold, a pouring device therefor, means for transferring a mold part to the receiving end of the runway and separating the cast plate for travel by gravity over the runway, movable means to stop the plate in the intermediate portion of the runway, separate means for finishing said plate by successively 40 shaving the concave face of the plate and severing one end thereof, means to divert the severed end of the plate from the runway, movable means to stop the plate in the lower delivery end of the runway, a power source and mechanism 45 for delivering power from said source in timed sequence to said pouring device, core-transferring means, plate finishing means, end diverting means and movable stop means.

2. In a stereotype plate making machine, an 50 inclined runway having an upper receiving end, a lower delivery end and an intermediate portion, a two-part casting mold, a pouring device therefor, means for transferring a mold part to the receiving end of the runway and separating the cast plate for travel by gravity over the runway, movable means to stop the plate in the intermediate portion of the runway, separate means for 55 finishing said plate by successively shaving the concave face of the plate and severing one end thereof, means to divert the severed end of the plate from the runway, movable means to stop the plate in the lower delivery end of the runway, a power source and a rotary cam device driven by said power source for operating said 60 pouring device, core-transferring means, plate finishing means, end diverting means and movable stop means in timed sequence.

3. In a stereotype plate making machine, an 65 inclined runway having an upper receiving end, 70 a lower delivery end and an intermediate portion, a two-part casting mold, a pouring device therefor, means for transferring a mold part to the receiving end of the runway and separating the cast plate for travel by gravity over the runway, movable means to stop the plate in the intermediate portion of the runway, separate means for finishing said plate by successively 75 shaving the concave face of the plate and severing one end thereof, means to divert the severed end of the plate from the runway, movable means to stop the plate in the lower delivery end of the runway, a power source and a rotary cam device driven by said power source for operating said pouring device, core-transferring means, plate finishing means, end diverting means and movable stop means in timed sequence.

a lower delivery end and an intermediate portion, a motor, a drive shaft operated by said motor, a two-part casting mold, a pouring device, means actuated by said drive shaft for operating the pouring device, means actuated by said drive shaft for unlocking the mold and tilting the mold core and cast plate onto the receiving end of the runway, means for stopping the plate and positioning it in the intermediate portion of the runway, finishing means driven from said shaft for successively shaving and trimming the plate, and means operated by said finishing means for diverting the severed end of the plate from the runway.

4. In a stereotype plate making machine, an inclined runway, a motor, a drive shaft operated by the motor, a two-part casting mold, a pouring device, means actuated by said drive shaft for operating the pouring device, locking means for the mold and mold core in their proximate positions, means actuated by the shaft for reciprocating the mold, and separate means actuated by the shaft for retracting the mold core, and tilting it past the runway.

5. In a stereotype plate making machine, an inclined runway, a motor, a drive shaft operated by the motor, a two-part casting mold, a rock shaft, means connecting the rock shaft to the drive shaft for oscillating movement, means actuated by the rock shaft for reciprocating the mold proper, a Geneva movement actuated by the rock shaft, and means connected with the Geneva movement for tilting the mold core past the runway.

6. In a stereotype plate making machine, an inclined runway, a motor, a drive shaft operated by the motor, a two-part casting mold, a rock shaft, means connecting the rock shaft to the drive shaft for oscillating movement, means actuated by the rock shaft for reciprocating the mold proper, a Geneva movement actuated by the rock shaft, rock arms supporting the mold core, and a link connecting one of said rock arms to the Geneva mechanism to tilt the mold core past the runway.

7. In a stereotype plate making machine, an inclined runway, a motor, a two-part casting mold, a pouring device therefor, means operated by said motor for operating said pouring device and transferring a mold part to the runway and separating the cast plate for travel by gravity over the runway, finishing means jointly actuated by the motor for shaving and trimming the plate, and means controlled by the finishing means for conveying the finished plate away and diverting the trimmed plate end.

8. In a stereotype plate making machine, an inclined runway, a motor, a two-part casting mold, a pouring device therefor, means operated by said motor for operating said pouring device and transferring a mold part to the runway and separating the cast plate for travel by gravity over the runway, a shaving arch over a portion of the runway, a rotary sleeve beneath the shaving arch and driven by the motor, a shaving knife carried by the sleeve, a rotary saw journaled on the sleeve behind the knife, a shaft journaled within the sleeve and transmitting rotation from the motor to the saw, a stop for the plate, and stop operating means on the sleeve.

9. In a stereotype plate making machine, an inclined runway, a motor, a two-part casting mold, a pouring device therefor, means operated by said motor for operating said pouring device and transferring a mold part to the runway and

separating the cast plate for travel by gravity over the runway, finishing means jointly actuated by the motor for shaving and trimming the plate, a stop for the plate, stop operating means actuated by the finishing means, a pivoted portion of the runway and means actuated by the finishing means for tilting said pivoted portion in timed sequence with the stop.

10. In a stereotype plate making machine, an inclined runway, a motor, a two-part casting mold, a pouring device therefor, means operated by said motor for operating said pouring device and transferring a mold part to the runway and separating the cast plate for travel by gravity over the runway, finishing means jointly actuated by the motor for shaving and trimming the plate, a stop for the plate, stop operating means actuated by the finishing means, a pivoted portion of the runway, a cam driven by the finishing means and a tiltable section of the runway operated by the cam in timed sequence with the stop.

11. In a stereotype plate making machine, an inclined runway, a motor, a two-part casting mold, a pouring device therefor, means operated by said motor for operating said pouring device and transferring a mold part to the runway and separating the cast plate for travel by gravity over the runway, a rotary sleeve actuated by the motor and having means for shaving and trimming the plate, a vertically reciprocable stop plate beyond the sleeve, a cam on the sleeve and means on the stop plate controlled by said cam.

12. In a stereotype plate making machine, an inclined runway, a motor, a two-part casting mold, a pouring device therefor, means operated by said motor for operating said pouring device and transferring a mold part to the runway and separating the cast plate for travel by gravity over the runway, a rotary sleeve actuated by the motor and having finishing means for shaving and trimming the plate, a cam, gearing between the cam and the sleeve, and a tiltable section of the runway operated by the cam in timed sequence with said finishing means.

13. In a stereotype plate making machine, the combination of a pouring device, a casting box associated therewith, means for reciprocating said box, a core, means for retracting and tilting the core during said retracting movement, a gravity runway for successively receiving the cast plate from the core, and positioning it for finishing and cooling, a movable stop for the cast plate intermediate said runway, a rotary sleeve underlying the plate, a knife carried by said sleeve for shaving the concave surface of the plate, a shaft journaled axially within the sleeve, a circular saw journaled on said sleeve behind said knife and driven from said shaft, a tilting section on the runway beyond the stop, means operated by said sleeve for tilting said section, a second stop spaced beyond said tilting section above the runway, means for rendering said stop inoperative, a power source and means connected thereto for cyclically and successively operating the several mechanisms.

14. In a stereotype plate making machine, an inclined runway having an upper receiving end, a lower delivery end and an intermediate portion, a two-part casting mold, a pouring device therefor, means for transferring a mold part to the receiving end of the runway and separating the cast plate for travel by gravity over the runway, movable means to stop the plate in the intermediate portion of the runway, separate

means for finishing said plate by successively shaving the concave face of the plate and severing one end thereof, means to divert the severed end of the plate from the runway, and movable means to stop the plate in the lower delivery end of the runway, a power source and mechanism for delivering power from said source in timed sequence to said plate finishing means, and diverting means and movable stop means.

15. In a stereotype plate making machine, an inclined runway having an upper receiving end, a lower delivery end and an intermediate portion, a two-part casting mold, a pouring device therefor, means for transferring a mold part to

- the receiving end of the runway and separating the cast plate for travel by gravity over the runway, movable means to stop the plate in the intermediate portion of the runway, separate means for finishing said plate by successively shaving the concave face of the plate and severing one end thereof, means to divert the severed end of the plate from the runway, movable means to stop the plate in the lower delivery end of the runway, a power source and a rotary cam device driven by said power source for operating said plate finishing means, end diverting means and movable stop means in timed sequence.

OSCAR C. ROESEN.
